UNITED STATES PATENT OFFICE

168,809

WALL POCKET OR THE LIKE

Mary Sapirstein, Bronx, N. Y.

Application September 8, 1951, Serial No. 16,579

Term of patent 3½ years

(Cl. D33—18)

To all whom it may concern:

Be it known that I, Mary Sapirstein, a citizen of the United States of America, residing at Bronx, in the county of Bronx and State of New York, have invented a new, original, and ornamental Design for a Wall Pocket or the like, of which the following is a specification, reference being made to the accompanying drawing, forming a part thereof.

Fig. 1 is a front elevational view of a wall pocket or the like showing my new design;

Fig. 2 is a top plan view; and

Fig. 3 is a side elevational view thereof

I claim:

The ornamental design for a wall pocket or the like, substantially as shown.

MARY SAPIRSTEIN.
